UNITED STATES PATENT OFFICE.

PIERRE MORELLINI, VICTOR DUPRAT, AND HENRI EISENSCHMIDT, OF LEVALLOIS-PERRET, FRANCE.

CARBURETOR FOR INTERNAL-COMBUSTION ENGINES.

Application filed November 2, 1921. Serial No. 512,311.

To all whom it may concern:

Be it known that we, PIERRE MORELLINI, VICTOR DUPRAT, and HENRI EISENSCHMIDT, the first a subject of the King of Italy and the other two being citizens of the French Republic, and all residing in Levallois-Perret, Seine, France, have invented certain new and useful Improvements in and Relating to Carburetors for Internal-Combustion Engines, of which the following is a complete specification.

This invention has for its object to provide an improved carburetor for internal combustion engines, designed in such a manner as to allow the liquid fuel to be drawn from the carburetor reservoir by the suction of the engine, thereby dispensing with any necessity for maintaining the liquid reservoir under pressure.

20 A constructional example of an improved carburetor according to this invention is illustrated in the accompanying drawings in which:

Fig. 1 is a vertical section on the line 1—1 of Fig. 2, and

25 Fig. 2 is a horizontal section on the line 2—2 of Fig. 1.

Fig. 3 is a vertical cross-section showing a modification of the carburetor.

30 Fig. 4 is a cross-section along the line A—A of Fig. 3.

Fig. 5 is a detail view in cross-section made approximately through a plane at right angles with that of Fig. 3.

35 Fig. 6 is a detail view of a link used in the carburetor.

As shown on Figs. 1 and 2, the improved carburetor comprises a container 1 of any suitable dimensions upon which are mounted 40 a sprayer 2 for normal running and a sprayer 3 for dead-slow running, both of which may have any desired dimensions. This container is closed at its upper part by a lid 4 fastened for instance by means of any suitable number of screws. In this lid there is formed a liquid fuel supply duct 5 connected by a pipe connector 6 to a duct (not shown) leading to a tank (likewise not shown) adapted to be mounted on a suitable 45 point of the car in the case where the invention is applied to motor-cars.

The duct 5 opens into a passage 7 provided in the wall 8 of a bell 9 arranged in an inverted position in the interior of the con-

tainer 1, and held in a suitable position by 55 means of screws 10 connecting its flange to the lid 4.

In the interior of the inverted bell 9 there is arranged a float 11 which is guided at its lower part by a stem 12 entering a cavity 60 in a recess in a projection on the bottom of the bell 9, and which comprises at its upper part a stem 13 terminating in a needle valve 14 adapted, in the upper position of the said float, to close the orifice of a duct 15 formed 65 in the lid 4 and opening into the suction pipe 16 of the carburetor, preferably between the usual throttle 17 and the engine.

In this duct 15 there is arranged an automatic valve consisting for instance of a ball 70 18 held in place by a plug 19. An air inlet duct 20 opening into the upper part of the bell 9 is likewise fitted with an automatically operating ball valve 21.

In the lower part of the bell 9 there is 75 formed a discharge aperture 22 provided with a closing valve 23 carried by a rocking lever 24 provided with a closing counter-weight 25 designed to keep the valve 23 in its closed position so long as the liquid fuel 80 has not reached a determined height in the interior of the bell 9.

The operation of this improved carburetor is as follows:—

During the working of the engine there 85 is created in the pipe 16 a partial vacuum which produces by way of the duct 15 a suction in the interior of the bell 9; this suction acting likewise by way of the duct 20 causes the valve 21 to bear against its 90 seat and thus shut off all communication between the interior of the carburetor and the atmosphere. This suction is transmitted through the passage 7 and the duct 5 into the petrol tank, and thus draws the petrol into 95 the bell 9. The petrol flowing into this bell raises the float 11, and when the petrol has reached a previously determined level the needle valve 14 carried by the float will be moved on to its seat so as to close the duct 100 15. Thereupon, since the engine suction can no longer exert any effect, the petrol ceases to flow into the bell 9, and since the ball valve 21 is not bearing against its seat, the valve will drop and allow air to enter 105 through the duct 20 into the bell 9. The valve 23 will thus open and allow the petrol contained in the bell 9 to flow into the con-

tainer 1. The aperture 22 is made of such a size that the discharge will empty the bell 9 quickly.

The bell 9 being empty, the float 11 will sink and uncover anew the connecting orifice between the bell 9 and the duct 15, so that the engine suction will act again anew in the bell 9 and in the petrol tank, thereby causing a fresh quantity of petrol 10 to flow into the bell and thence into the container 1.

This operation is repeated indefinitely, the petrol being drawn into the bell 9 by the engine suction, and then delivered into 15 the container 1 whence it passes to the sprayers in the usual manner.

During the whole period that the engine is sucking petrol or other liquid fuel from the tank, the valve 21 is closed, thus preventing 20 all communication between the carburetor and the atmosphere, whereas the said valve will open immediately the needle valve 14 shuts off the communication with the engine suction pipe.

25 The ball valve 18 situated in the duct 15 is intended to prevent any striking back of the flame into the carburetor. If, owing to the defective operation of the engine, there should be a striking back of the flame 30 in the passage 16, the suction in this passage will cease, so that the valve 18 will drop back upon its seat and thus effectually prevent the flame from reaching the carburetor. A non-return valve not shown will 35 be provided in the pipe connector 6 for preventing the liquid fuel in the carburetor from returning into the tank in the case of the car assuming an inclined position.

In the constructional form of Figs. 3 to 40 6, the carburetor comprises a container *a* of any suitable dimensions, provided with the usual sprayers for normal running and for dead-slow running. The said container is closed at its upper part by a lid *b* which 45 may be fastened by any device, for instance by a screw not shown on the drawings. Upon the underside of the said lid is secured a hollow cylinder *c* which is closed at its lower part by a bottom *d* which may be 50 for instance screwed in the said cylinder.

Provided in the lid is a duct *e* connected by a canal *f* with a passage *g* provided in the wall of the carburetor body, and opening 55 into a circular groove *h* provided in the part *i* connecting the carburetor with the motor not shown. The said groove is provided opposite another similar groove provided in a ring *r*, and bored in the said groove *i* are several apertures *j* arranged in a crown on the external surface 60 of the said ring *i*, the said apertures being thus connected with the suction canal of the motor.

The duct *e* opens into the inner part 65 of the cylinder through an orifice provided

with a self closing valve *k*, constituted by a ball resting under its own weight upon the upper end of a canal *m*, the lower end of which forms a seat for a pin *n* carried upon a float *o* which is guided through its 70 lower part by a second rod the lower end of which is pointed and forms a valve *p* which may close the canal *q* controlling the flowing out of the liquid fuel which canal opens into a seat *r* the position of 75 which may be regulated.

Arranged upon the upper side of the float *o* is a vertical rod *s*, which may act upon a valve *t* opening into the open air and which thus may connect the inside of 80 the container with the atmosphere. A passage *t* provided in the wall of the cylinder *c* is connected with the fuel tank (not shown) through a convenient piping.

The sprayer *n* for normal running opens 85 into the suction canal of the motor through a movable venturi *v* which conveniently chokes the said canal and is provided with openings *w* which may be brought into coincidence with openings *x* of the wall of 90 the throttle valve chamber *y*. Connected with the venturi *v* is a controlling part by which the position of the said ring may be regulated, as well as the quantity of air admitted through the orifices *w*. 95

The several parts may be controlled by the aid of small links, the said links being made in two parts (Fig. 6) connected by means of a conical surface *z*, the said parts being provided with convenient screws 100 or bolts permitting the said parts to be strongly connected together.

The operation of the said modified carburetor is as follows:

During the working of the engine, there 105 is created through the canals *g*, *e*, in the inner part of the cylinder *c* a partial vacuum which produces by way of the duct *t* a suction in the interior of the fuel tank: the cylinder *c* being empty, the float 110 occupies the position shown in Fig. 3, the valve *p* closing the orifice *q* controlling the exit of the fuel and the valve *n* closing the suction orifice *m*. The ball valve *k* is opened by the suction of the motor 115 for allowing the said suction to operate upon the liquid fuel which then comes and fills the cylinder *c*.

The level of the fuel raises in the said cylinder, causing the float *o* to close the suction duct *m* and to open the orifice *q* for the flowing out of the petrol, whilst the rod *s* raises the valve *t*, thus bringing the inside of the cylinder into communication with the atmosphere. Then, the petrol contained in 120 the cylinder *c* flows into the container *a*, the float is lowered, thus closing anew the orifice *q* and opening the orifice of the suction canal *m*, while the valve *t* being no longer supported by the rod *s* rests upon its 125 130

seat. The suction is again produced through the cylinder *c* into the fuel tank and the operation is indefinitely resumed.

The liquid fuel is brought by the sprayer 5 *u* into the chamber *y*, and in the said chamber, according to the position of the venturi *v* there is produced through the orifices *w* a supplementary entrance of air which 10 operates a more complete mixing of the combustible mixture, thus favoring the operation of the motor and saving the fuel.

The arrangement of the venturi *v* and of the ring *r*, renders the mixture more homogeneous, owing to the two choking actions 15 provided by those parts and which are separated by an expansion chamber.

The foregoing description of the improved carburetor is given solely by way of example. It is to be understood that the 20 forms of the parts may be varied without departing from the essential nature of the invention.

Having now particularly described and ascertained the nature of our said invention 25 and in what manner the same is to be performed, we declare that what we claim is:—

1. A carburetor of the character described, comprising a main fuel chamber having spraying devices, a relatively small 30 fuel chamber suspended in the main chamber and having an opening in its bottom and a passage in its wall opening into the bottom thereof and connected with the fuel supply, a connection between the small 35 chamber and the suction pipe of the motor, a self closing valve in said connection, a float having guided movement in the small chamber and provided with a needle valve

controlling the said connection, an air inlet opening into the small chamber and provided with a self-closing valve held to its seat by the suction and a counter weighted valve mounted on the outer side of the bottom of said small chamber and opening when air is admitted to the said chamber 45 to allow all the fuel drawn into the said chamber to be discharged into the main chamber.

2. A carburetor of the character described, comprising a main fuel chamber 50 having spraying devices, a relatively small fuel chamber suspended in the main chamber and having an opening in its bottom and a passage in its wall opening into the bottom thereof and connected with a fuel supply, a connection between the small chamber and the suction pipe of the motor, a ball valve in the connection, a float having guided movement in the small chamber and provided with a needle valve controlling the 55 said connection, an air inlet opening into the small chamber and provided with a ball valve held to its seat by the suction, and a counterweighted valve mounted on the outer side of the bottom of the small chamber and opening when air is admitted to the said chamber to allow all the fuel drawn into the said chamber to be discharged into the main chamber.

In testimony we have hereunto set our 60 hands at Paris, France, this 21st day of October, 1921.
